UNITED STATES PATENT OFFICE

137,520

DESIGN FOR AN ELECTRIC WELDING ROD HOLDER

Florian E. Trinajstich, Los Angeles, Calif.

Application August 28, 1943, Serial No. 111,121

Term of patent 7 years

(Cl. 26—1)

To all whom it may concern:

Be it known that Florian E. Trinajstich, a citizen of Austria, residing at Los Angeles, in the county of Los Angeles and State of California, has invented a new, original, and ornamental Design for Electric Welding Rod Holder, of which the following is a specification, reference being had to the accompanying drawing forming a part thereof, in which:

Figure 1 is an elevational view of an electric welding rod holder showing my new design.

Figure 2 is an end view thereof taken from the line 2—2 of Fig. 1.

Figure 3 is a sectional view thereof taken through 3—3 of Fig. 1.

Figure 4 is an end view thereof taken from 4—4 of Fig. 1.

I claim:

The ornamental design for an electric welding rod holder, as shown.

FLORIAN E. TRINAJSTICH.
